BASE FOR A CIGARETTE LIGHTER

John E. Haaland, 4122 Coffman Lane, Minneapolis, Minn.
55406, and Carl P. Graf, P.O. Box 591A, Forest Lake,
Minn. 55025

Filed Nov. 8, 1968, Ser. No. 14,370

Term of patent 14 years

Int. Cl. D27—05

U.S. Cl. D48—27

FIGURE 1 is a rear elevation of the base for a cigarette lighter of the invention;

FIGURE 2 is a right side elevational view of the base for a cigarette lighter;

FIGURE 3 is a front elevation of the base for a cigarette lighter;

FIGURE 4 is a top plan view of the base for a cigarette lighter;

FIGURE 5 is a transverse sectional view taken on line 5—5 of FIGURE 2;

FIGURE 6 is a right side elevation of a modified form of base for a cigarette lighter;

FIGURE 7 is a transverse section on the line 7—7 of FIGURE 6 and in the direction of the arrows;

FIGURE 8 is a right side elevation of another modified form of base for a cigarette lighter; and

FIGURE 9 is a transverse section on the line 9—9 of FIGURE 8 and in the direction of the arrows.

The undisclosed sides of the second and third embodiments are substantially the same as the sides shown in FIGURES 6 and 9, respectively.

The front and rear of said embodiments are substantially the same as that of the first embodiment as shown in FIGURES 1 and 2.

The flame emitting cap and the switch are shown in broken lines for illustrative purposes only.

We claim:

The ornamental design for a base for a cigarette lighter, substantially as shown and described.
